DESIGN FOR A CLUB HEAD

Carl F. Hogelund, Minneapolis, Minn.

Application February 20, 1932. Serial No. 42,944

Term of patent 3½ years

To all whom it may concern:

Be it known that I, CARL F. HOGELUND, a citizen of the United States, residing at Minneapolis, in the county of Hennepin and State of Minnesota, have invented a new, original, and ornamental Design for Club Heads, of which the following is a specification, reference being had to the accompanying drawing, forming part thereof.

Fig. 1 is a perspective view of a club head showing my new design;

Fig. 2 is a plan view of the club head.

Fig. 3 is an elevational view of the club head, and

Fig. 4 is a transverse sectional view taken on line 4—4 in Fig. 2.

I claim:

The ornamental design for a club head as shown.

CARL F. HOGELUND.
